AUTOMATIC PARKING METER

Gerald A. Hale, Oklahoma City, Okla., assignor of one-fourth to Carl Magee, Oklahoma City, Okla., one-fourth to George A. Nicholson and one-fourth to John B. McGay, both of Tulsa, Okla.

Application October 1, 1945, Serial No. 619,477

13 Claims. (Cl. 194—54)

1

This invention relates to an automatic parking meter for indicating the parking time on city streets, and more particularly but not by way of limitation to an automatic parking meter which is operable on more than one denomination of coins, and which will operate by multiple coins of each of a selected denomination.

In the majority of the conventional coin operated parking meters utilized today which function automatically upon insertion of a coin, the coin tripping is through the force exerted by the weight of the inserted coin which requires a mechanism providing a delicate trip action due to the small weight of the coins such as pennies and nickels utilized. A parking meter operates outdoors under all weather conditions, and the utilization of a delicate trip mechanism actuated by the coin weight has been found to be inefficient and providing a faulty source of operation which in many instances will fail to function completely. Furthermore, modern day parking meters depend on gravity to carry the coin through at least part or all phases of the coin operation. This is detrimental since infiltrated moisture, freezing conditions, and the accumulation of traffic dust and debris will effect the efficiency of operation where dependence of operation is placed on coin gravitation. In the prior patents to Michaels, No. 2,329,926 and the patents to Toce et al., Nos. 2,340,441 and 2,340,442 and McGay No. 2,284,221, all provide a coin trip lever to cause re-setting of the time indicator and as such are subject to the detriments mentioned supra.

The present invention broadly provides a parking meter which operates to release a coin actuated lever by the force of the operator's finger through the coin inserted in a coin slot. Furthermore, the time indicator is released to return to a starting position under the energy of a spring, such starting position being regulated by a predetermined stop mechanism cooperating with the coin operated lever. The time indicator is connected to a gear train of a time means, however, upon operation of the coin operated lever the indicator is disengaged from the clock train which allows re-setting thereof to a predetermined stop position. After re-setting, the indicator is then re-engaged with the clock train to cooperate with the clock in determining the parking time utilized.

It is an important object of this invention to provide a parking meter which is operable on more than one denomination of coins as well as multiple coins of each of the denominations.

2

A further object of this invention is to provide a parking meter which can be adjusted for operation with various combinations of coins or multiples of coins and preferably in combinations of five pennies and one nickel or ten pennies and two nickels.

A further object of this invention is to provide a parking meter which automatically functions upon the insertion of a coin wherein the coin is forced into the meter from the operator's fingers to cause actuation of a coin trip lever which releases a coin propelling mechanism to provide actuation of the meter.

A further object of this invention is to provide a parking mechanism whereby the coin is forced into the meter from operator's finger to cause actuation of a power driven coin propelling element which picks up the coin and is carried a predetermined distance dependent upon the denomination of the coin in order to operate an indicator stop unit for re-setting the time indicator complementary to the value of the coin inserted.

An additional object of this invention is to provide an automatic parking meter wherein insertion of a coin under the force of the operator's finger moves a coin trip lever which in turn only serves to release a power driven coin propelling element of the mechanism thereby eliminating the use of the weight of the coin for tripping the mechanism into operation thereby producing a tripping action which is more positive, simple and durable.

An additional object of this invention is to provide an automatic parking meter which has a power driven element released through insertion of the coin into the mechanism which operates to re-set a time indicator in complement to the value of the coin and will also display the coin to decrease the possibility of utilizing slugs in the mechanism.

And still another object of this invention is to provide an automatic parking mechanism wherein the mechanism for re-setting the time indicator is released to operate and not forcibly moved through a fixed distance.

And still another object of this invention is to provide an automatic parking mechanism which allows immediate re-setting of a time indicator upon the successive insertion of multiple coins of like or different denominations and which is adjustable to provide for numerous combinations of each denomination of coin.

Another object of this invention is to provide an automatic parking mechanism which includes

a stop pawl mechanism for limiting the position of the time indicator in one direction, wherein said pawl mechanism is provided with a cushioned backlash action to allow the pawl upon disengagement from a tooth to move ahead of the previously engaged tooth on the indicator ratchet thereby preventing jamming of the pawl against a tooth upon successive insertion of multiple coins of like or different denominations.

And an additional object of this invention is to provide an improved parking meter which is automatic and more durable in its operation, simple in construction and facilitates the maintenance and adjustment thereof.

Other objects and advantages of the invention will be evident from the following detailed description read in conjunction with the accompanying drawings which illustrate my invention.

In the drawings:

Fig. 1 is a front elevational view of the mechanism with certain parts broken away and showing the elements in the normal position which they occupy before a coin is inserted into the meter.

Fig. 2 is a fragmentary front elevational view similar to Fig. 1 and with the elements shown in the position they occupy after the insertion of a coin into the meter.

Fig. 3 is a side elevational view partly in section taken from the right of Fig. 1 and with certain parts omitted for clarification.

Fig. 4 is a detailed view of the clutch releasing means of the time indicator.

Fig. 5 is a view similar to Fig. 4 with certain parts broken away showing the engagement of the clutch mechanism with the time indicator.

Fig. 6 is a detailed view showing the stop pawl mechanism at a position of dis-engagement with the ratchet sector for the time indicator.

Fig. 7 is a similar view showing the pawl moving into position of engagement.

Fig. 8 is a similar view showing the pawl engaging the lowermost teeth of the ratchet.

Fig. 9 is a similar view showing the pawl engaging one of the higher teeth of the ratchet denoting use of a large denomination of coin.

Fig. 10 is a detailed view showing the arrangement of the expired flag. The full lines denoting the flag in rest position while the dotted lines show it in operating position.

Fig. 11 is a detailed view similar to Fig. 6 but showing a modification using a masking ring on the ratchet sector.

Referring to the drawings in detail and more particularly Figs. 1, 2 and 3, reference character 2 designates a parking meter mechanism adapted to be encased as a unit in a housing (not shown). The case or housing forms no part of this invention. The mechanism 2 comprises a pair of spaced plates 3 and 4 forming the outer frame work of the mechanism. A main spring housing 5 is disposed in the lower half of the space between the plates 3 and 4 and includes a main spring 6. The spring and housing are supported between the plates 3 and 4 by a shaft 7 secured in the frame plates. One end of the shaft 7 projects outwardly from plate 4 and is preferably formed with a square end 8 to provide a winding square for the spring 6. The rotatable shaft 7 is provided with a main gear 9 which in turn drives a freely rotatable compound pinion with a gear 10 mounted on a main drive shaft 12 fixed between the frame plates 3 and 4. A clock works 13 is secured by locking studs 14 to the rear of plate 4. A clock shaft 18 extends

from the clock mechanism 13 and is loosely anchored between the plates 3 and 4. The shaft 18 is provided with a pinion 19 adapted to mesh with the gear 10, thereby providing a connection for driving the clock works 13 from the main spring 6. A substantially annular dial 20 is disposed above the plates 3 and 4 by an extension 21 adapted to be secured (not shown) to the plate 4. Both front and rear faces of the dial 20 are scaled at 22 to show a total of two hours' parking time divided into ten minute intervals. The time dial 20 is provided with an aperture 23.

The main shaft 12 extends through the front plate 3 and on its outer end is provided with a circular coin propelling plate 24 disposed in spaced relation to the plate 3. Plate 24 is secured to the shaft 12 by a nut 24a. An auxiliary gear 26 rigidly disposed on the shaft 7 meshes with a pinion 27 mounted on shaft 12 to provide a driving connection for the coin propelling plate 24 from the energy of the main spring 6. The outer periphery of the plate 24 is provided with a plurality of gear teeth 24b adapted to mesh with a gear 32 of a fan type governor for a purpose as will be hereinafter set forth. From the foregoing it will be apparent that the main spring 6 provides a source of energy for both the clock works and the coin propelling plate, the function of which will be hereinafter explained. The plate 24 is provided with a plurality of projecting studs 28 preferably spaced 90° apart. In addition, a second set of projecting studs 29 are secured to the plate 24 and are preferably spaced circumferentially 90° apart, however they are disposed in spaced relation both radially and circumferentially to the respective studs 28 as will be hereinafter set forth. The plate 24 is also provided with a plurality of spaced apertures 30 preferably four in number, acting as display windows for the coins. The main plate 3 is provided with an outwardly projecting flange 31 (Figs. 1 and 3) providing coin slot 31a for receiving the coins. The flange extends partially around the plate 3 to cover the space 25 between the plates 3 and 24 so that upon insertion of a coin it cannot fall out the sides between the plates but will be guided through its operation as will be hereinafter set forth. The plate 3 is provided with a circular raised portion 31b acting as the bottom portion of a coin guide-way in space 25 between the portion 31a and flange 31. A pair of plates 35 and 36 (Fig. 2) are adjustably secured by the stud 37 to the front plate 3 and are disposed at a slightly angled relation to each other. The plate 35 is superimposed on the plate 36, and each of the plates is provided with a cam or curved surface cooperating with the coin as will be hereinafter mentioned.

A coin trip lever 38 is pivoted at 39 to the plate 3 and has its top portion 40 disposed in the space 25 immediately adjacent the entrance to the coin slot 31a. The lever 38 is held in this position under tension of a spring 41 anchored at one end of the lever 38 and at its opposite end to a stud 42 provided on the plate 3. The lever 38 has a turned-down portion forming a projection 43 adapted to contact a lug 28 to prevent rotation of plate 24 until insertion of a coin. A coin actuated lever 45 is loosely mounted on the main shaft 12 immediately behind the gear 27 and is provided with an outwardly projecting stud 46 extending over the space 25 between the plates 3 and 24. The stud 46 extends through an aperture 48 in plate 3

which acts as a guide-way for the stud 46 as will be hereinafter set forth. The lever 45 is normally held in the lowermost portion of the guide-way 48 under tension of a spring 49 anchored at one end to the lever 45 and at its opposite end to a stud 50 provided on plate 3. As shown in Figs. 4 to 9 inclusive, a portion of the lever 45 is formed to provide a drop cam 51 having a recess or notch 52 cooperating with a projecting stud 53 of an idler lever 54. A spring 55 urges the lever 54 into engagement with the cam 51. The spring is anchored to a stud 55a on a frame plate in a manner not shown.

A rotatable shaft 56 is secured between the plates 3 and 4 on which is loosely mounted the idler lever 54. A time indicator 58 having a lower sector 59 substantially disc shaped is rigidly mounted to the shaft 56 immediately adjacent and parallel to the idler lever 54. A substantial portion of the outer periphery of the sector 59 is provided with gear teeth 60 for a purpose as will be hereinafter set forth.

A ratchet sector 62 as clearly shown in Figs. 6 to 9 inclusive, is secured to the shaft 56 in slight spaced relationship to the indicator 58 and is provided with a plurality of annular ratchet teeth 63. The teeth 63 comprise two sets of four shallow teeth 64, and two longer teeth 65, all spaced apart to denote twelve minutes time thereby allowing for utilization of ten pennies or two nickels and two hours parking time as will be hereinafter set forth. Both teeth 64 and 65 form penny stop positions while teeth 65 only form nickel stop positions. Cooperating with the ratchet 62 is an indicator stop unit comprising a stop pawl arm 63 secured to a shaft 68 anchored between the plates 3 and 4. A pitman 70 is connected at one end through slot 71 to a stud 72 on pawl arm 68 and at the opposite end is anchored by a stud 77 to the coin actuating lever 45. One end of the pawl arm 68 is provided with a pawl 73 which is urged in a counterclockwise direction according to Figs. 4 to 9 inclusive under tension of a spring 74 anchored at one end to the pawl 73 and at the opposite end to a stud 75 provided (not shown) on the plate 3. A slot 76 is provided in the pawl arm 68 receiving shaft 69 to provide a cushioned backlash as will be hereinafter explained.

Referring further to the indicator sector 59 from Figs. 3, 4 and 5, it will be apparent that the teeth 60 mesh with a freely rotatable idler gear 78 secured to the idler lever 54 by a stud 79. The gear 78 in turn is adapted to mesh with a gear 80 rigidly disposed on clock shaft 18, when the coin actuated lever 45 is in rest position Fig. 5 as will be hereinafter set forth. In this manner the indicator is moved at a constant rate by action of the main spring 6 and timer 13 during the time measuring period.

The auxiliary shaft 56 is provided with a torsion spring 82 adapted to constantly force the shaft 56, indicator 58 and ratchet 62 in a direction opposite the clock drive toward the two hour scale on the dial 20. One end 83 of the spring 82 bears against a grooved supporting stud 84 disposed between the sector 62 and the indicator 58.

Referring to Figs. 3 and 10, a flag 86 having a sector 87 denoting expired time on the meter is loosely mounted on the shaft 56. One end portion of the flag 86 is provided with a counterweight 88 for a purpose as will be hereinafter set forth.

General operation

It is thought that the detailed description supra clearly sets forth the various elements of the mechanism and the operation thereof will now be explained. Assuming that either a penny or nickel is inserted in the coin slot 31A and the force of the operator's fingers applied through the coin as the coin is being inserted is sufficient to move the trip lever 38 in a counterclockwise direction according to Fig. 1 against the tension of spring 41 thereby releasing the lever from lug 28 to allow a rotation of the coin propelling plate 24 by energy of the main spring 6. The coin is then contacted and moved by lug 28 into contact with the stud 46 of the lever 45 and propelled by plate 24 partially through an arc of 90° into contact with the cam plates 35 and 36. The distance between the cam surface 90 of plate 35 and stud 46 is less than the diameter of a penny as well as a nickel, while the distance between the cam surface 91 on plate 36 and stud 46 is greater than the diameter of a penny but smaller than the diameter of a nickel for a purpose as will be hereinafter set forth. The lever 45 is rotatable around shaft 12 and is moved from a rest position A through four possible stages as will be hereinafter explained. The lever 45 is moved counterclockwise according to Fig. 1 against tension spring 49 until the coin drops off the cam faces of plates 35 or 36 depending on the denomination where it is brought by lug 28 into display position at window 30. Lugs 29 are positioned in the path of the coin and prevent movement of the coin beyond the display position until the next operation. Movement of the lever 45 from a rest to an operating position as shown in Figs. 4 to 9 inclusive, causes the stud 53 of idler lever 54 to ride the highest arcuate portion of cam 51 thereby moving lever 54 and gear 78 out of contact with clock gear 80 so that the indicator 58 will be released to move under force of spring 82 in a clock-wise direction according to Fig. 1 and opposite to that of the clock drive to cause a re-setting of the indicator in complement with the value of the coin. The stop pawl 73 and its associated mechanism cooperates with the released time indicator 58 through ratchet 62 to reset the indicator in accordance with the denomination of the coin inserted. The indicator stop unit is such that movement of the coin actuated lever 45 moves the pawl pitman 70 in a direction similar to the lever 45 whereby slot 71 allows releasing of the pawl arm 68 and the pawl 73. The pawl through energy of spring 74 (Figs. 6, 7 and 8) is then directed into contact with the teeth 63.

With the pawl 73 released to contact a particular tooth 63 dependent upon the denomination of the coin, the indicator is re-set relative to the dial 20 for a specified time limit. It will be apparent during rotation of the coin by plate 24, the cam plates 35 and 36 cooperate with the lever stud 46 to hold the coin in such relation to the lever 45 that the lever is moved by the coin through a pre-determined distance depending on the denomination of the coin. When the coin is moved to a display position the coin actuated lever 45 is free to return to rest position under tension of spring 49. In returning the lever to rest position as shown in Fig. 5, the stud 53 of idler lever 54 is urged by spring 55 into notch 52 thereby placing idler gear 78 in contact with clock gear 80, and bringing the indicator 58 under the constant drive action of the timer 13. Si-

multaneous with a return movement of lever 45 under tension of spring 49, toward a position of rest, the lever 45 through pitman 70 disengages the pawl 73 from the particular tooth contacted.

It will be apparent that the clutch means indicated by cam 51, idler 54, idler gear 78, upon the return of lever 45 to rest position first re-engages the indicator and then the pawl 73 is dis-engaged from the ratchet teeth 63. In moving away from the teeth 63 the pawl 73 functions to completely clear the teeth 63 so that if a second coin is inserted immediately after the first coin such as multiple pennies or multiple nickels or both, the indicator stop action is such that the pawl will move over the particular tooth which it had previously engaged. This "jump-action" of the stop pawl over each tooth on successive coin insertions is accomplished in the following manner. From Figs. 6 to 9 inclusive, the pawl arm 68 is provided with the elongated aperture 76 which permits a slight retardation of the pawl arm 68 by force of sector 62 when contacting a tooth 63 as is clearly shown in Fig. 8 thereby positioning the stud 69 in the upper portion of the elongated slot 76. With the operation completed and the pawl moved away from contact with the engaged tooth, the pawl arm 68 under tension of spring 14 will slide on shaft 69 due to the slot 76, thereby permitting a moving or jumping of the pawl 73 ahead of the tip of the tooth 63 previously contacted, and in position to engage the next successive tooth 63 upon insertion of another coin. This action will occur on successive nickels as well as successive pennies since the moving of the pawl away from the teeth will allow clearance of the low teeth 64 on penny operations as well as the high teeth 65 on nickel operations as will be hereinafter explained. This provides for successive insertions of different denominations of coins, and with the pawl being released by the pitman 70 jamming is prevented.

Penny operation

Assuming that a penny is inserted in the mechanism, the operation in accordance with Figs. 6, 7 and 8 is such that the lever 45 is moved from the position designated at A to a position B whereby the pawl is completely released and allowed to contact a notch 92 on sector 62 flush with the bottom of the first tooth 64. Continued movement of lever 45 from position B to C disengages the idler gear 78 from gear 80 allowing rotation of indicator 58 under energy of spring 62 to bring the front tooth of one set of teeth into contact with the front face of the pawl 73 thereby denoting twelve minutes' time on the dial 20. In this position (Fig. 8) the slot 76 provides a spring cushioned backlash so that upon the immediate insertion of another coin, either a penny or nickel, the lever 45 and associated mechanism will permit the pawl 73 to move ahead of the first tooth in set 64 in order to contact a successive tooth depending upon the denomination of the coin. If another penny or multiple pennies are inserted, the pawl 73 will be moved to repeat the operation against each succeeding tooth 64 to set the indicator on a tooth 64 corresponding to the total number of pennies inserted. However, if a nickel is inserted following a penny insertion the pawl will function at position C the same as for a penny operation but upon continued movement as shown in Fig. 9, jumps ahead of all the teeth 64 to be placed in contact with the first high level tooth 65. As previously mentioned, with the lever in position C, the penny is allowed

to ride off the cam face 90 of plate 35 releasing the lever 45 from contact with the penny in order to return to position A under action of spring 49. The plate 24 continues rotation and through lugs 5 29 brings the penny to a position of display in window 30.

Nickel operation

With the insertion of a nickel in the coin slot 31 the lever 45 is rotated in a similar manner with the various elements operating as explained supra. As shown in Figs. 7 to 9 inclusive the lever in moving from position A to a position D the pawl 73 is released at position B and is brought into contact with the groove 92 and the first tooth 64. Continued movement of the lever 45 and stud 46 from a position B on to position D moves the pitman 70 and stud 77 counterclockwise according to Figs. 8 and 9 whereby the pitman 70 disengages the pawl from the first tooth 64 and positions the pawl slightly above the low level teeth 64 until such time that a high level tooth 65 is brought into contact with the front face of the pawl 73. In this position the indicator 58 is moved to a position on the dial 20 denoting one hour parking time. Furthermore, the nickel has moved past (Fig. 1) the cam surface 91 of the cam plate 36 to be positioned by lug 28 in the display window 30. It will be apparent that rotation of plate 24 through an arc of 90° upon each coin insertion will allow movement of a previously inserted coin from a display position at the top of plate 24 to a display position window 30 at the left of the mechanism as shown in Fig. 1. This provides multiple display of coins having the advantage of decreasing the possibility of using slugs in the meter. With the stud 46 of lever 45 released by movement of the nickel to display position it returns in guide-way 48 under action of spring 49, however, it will be apparent that the jumping action provided by slot 76 on pawl arm 68 will allow the pawl 73 to move beyond the high level tooth 65 to be ready for engagement with the second set of teeth 63 beyond the first high level tooth 65 irrespective of the denomination of the coin inserted.

Alluding further to the rotating plate 24, it will be apparent that the teeth 24-b engage the teeth of a fan type governor gear 32 secured in bracket 93 to the plate 3. The governor functions to limit the speed of rotation of the plate 24 upon being released by the trip lever 38 through the insertion of a coin.

Referring to Fig. 11 a modification is shown of the ratchet sector 62 provided with a masking ring 94 having a plurality of small teeth 95. This masking ring may be secured to the sector 62 when it is desired to mask out the low level teeth 64 for the penny operation thereby providing the nickel operation only. Furthermore, it will be apparent that a portion of the low level teeth 64 may be masked out by the ring 94 where it is desired to use only one penny and one nickel or two pennies or any number desired in lieu of the five penny operation.

Fig. 10 discloses the operation of the expiration signal 87 provided with a leg 86 loosely mounted on shaft 56. One end of the leg is provided with a counterweight 88. A latching member 98 is loosely secured to a stud 99 anchored in plate 3. The latch 96 is provided with a latching lug 100. A spring 98 is anchored to a stud 102 for urging the lug 100 toward the shaft 56. A spring 103 is anchored between the leg 86 and the actuating lever 45. The indicator 58 is provided

with a projecting stud 97. As shown in Fig. 10 with the indicator 58 re-set to denote any measurement of time on the dial 20, the expired flag is in an inoperative position as shown by the full lines, however as the indicator moves counter-clockwise as shown in Fig. 10 toward the expiration of time, the stud 97 is moved up into position to contact the upper leg of latch 96 causing it to rotate or pivot about stud 99, and move lug 100 away from the end portion of leg 86 whereby the counterweight 82 rotates the flag 87 into an upright position as shown in the dotted lines in Fig. 10. The rotation of the flag 87 into an upright or vertical position is against the action of the spring 103. With an insertion of a coin into the meter and the re-setting of the indicator, movement of the lever 45 to the position D causes the spring to move the flag 87 into an inoperative position where it is latched by lug 100 until such time the indicator 58 fails to show any time remaining on scale 20.

Referring to Fig. 1, the rotation of the coins by the plate 24 in 90° cycles will eventually bring a coin from the last display position of a display window 30 to where it is allowed to drop in a coin chute 105 communicating with a coin box (not shown).

From the foregoing, it will be apparent that the invention provides an automatic parking meter based on the principle which permits the coin trip action to be by the force of the operator's finger applied through the coin as the coin is inserted in the coin slot. In this manner, the actuation of the coin trip lever does not itself or through the weight of the coin cause the re-setting of the indicator but the re-setting is accomplished by the release of a coin propelling plate, whereby the re-setting action takes place later in the cycle of operation as the coin is moved through the mechanism, thereby making the tripping action more positive, simple and reliable. Furthermore, the present mechanism provides a meter which is operable on more than one denomination of coins and which will operate on multiple coins of each of the selected denominations. The meter is easily adjustable for any possible combination of coins and multiple coins. Furthermore, the mechanism provides releasing of the indicator for returning to a starting position in a manner which utilizes an indicator stop action operated through its connection with the coin operated lever, coin and coin propelling plate. The indicator stop action principle is that the stop pawl is only released to engage the indicator ratchet and is not forcibly moved through a fixed distance. In this manner, if a second coin is immediately inserted after a first coin, the pawl is moved ahead of a previously engaged tooth through a spring cushioned backlash to allow for the successive insertion of coins. This moving ahead will occur on successive nickels as well as successive pennies, thereby providing a stop action which is simple in operation and construction to provide a meter which can be operated on both multiple pennies or multiple nickels.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. In an automatic parking meter adapted to receive multiple coins of different denominations for indicating selective amounts of time and comprising a movable indicator, a clock works for driving the indicator in one direction relative to a time scale, a ratchet movable with the indicator and provided with a plurality of sets of various sized teeth corresponding to coins of different denominations, means for urging the indicator and ratchet in a direction opposite the first mentioned direction to reset the indicator, indicator stop means cooperating with the ratchet in one position of the stop means to limit the resetting movement of the indicator in said last mentioned direction, coin actuated means normally retaining the indicator stop means out of engagement with the ratchet, said coin actuated means being responsive to a coin inserted in the meter for releasing the indicator stop means to allow engagement thereof with at least one set of ratchet teeth, and means provided in the indicator stop means providing successive resetting of the indicator upon successive insertion of multiple coins of different denominations.

2. In an automatic parking meter adapted to receive multiple coins of different denominations for indicating selective amounts of time and comprising a movable indicator, a clock works for driving the indicator in one direction relative to a time scale, a ratchet movable with the indicator and provided with a plurality of sets of various sized teeth corresponding to coins of different denominations, means for urging the indicator and ratchet in a direction opposite the first mentioned direction, indicator stop means cooperating with the ratchet in a released position of the stop means to limit the movement of the indicator in said last mentioned direction, coin actuated means normally retaining the indicator stop means out of engagement with the ratchet, said coin actuated means responsive to a coin inserted in the meter for releasing the indicator stop means to provide selective engagement thereof with the ratchet teeth, means provided in the indicator stop means providing successive resetting of the indicator upon successive insertion of multiple coins of different denominations, and means cooperating with the coin actuated means to disengage the clock works from the indicator during re-setting of the indicator.

3. In an automatic parking meter adapted to receive multiple coins of different denominations for indicating selective amounts of time and comprising a movable indicator, a clock works for driving the indicator in one direction relative to a time scale, a ratchet movable with the indicator and provided with separate sets of teeth complementary to the different denominations of coins, pawl means cooperating with the ratchet in a released position of the pawl means to limit movement of the indicator in a direction opposite the first mentioned direction, means re-setting the indicator and ratchet in said last mentioned direction, means adapted to rotate a coin upon insertion thereof into the meter, means normally retaining the pawl means out of engagement with the ratchet and cooperating with the coin rotating means through the medium of the coin for releasing the pawl means into selective engagement with the teeth of the ratchet in accordance with the denomination of the coin, means provided in the

11

pawl means to provide movement of the pawl means beyond the previously engaged tooth upon movement of the pawl means away from the tooth, thereby providing engagement of the pawl means with a subsequent tooth upon insertion of a subsequent coin in the meter, and indicating an extended time on the time scale.

4. In an automatic parking meter adapted to receive multiple coins of different denominations for indicating selective amounts of time and comprising a movable indicator, a clock works for driving the indicator in one direction relative to a time scale, a ratchet movable with the indicator and provided with separate sets of various sized teeth complementary to the different denominations of coins, pawl means cooperating with the ratchet in a released position of the pawl means to limit movement of the indicator in a direction opposite the first mentioned direction, means re-setting the indicator and ratchet in said last mentioned direction, means adapted to rotate a coin upon insertion thereof into the meter, means normally retaining the pawl means out of engagement with the ratchet and cooperating with the coin rotating means through the medium of a coin inserted in the meter for releasing the pawl means into selective engagement with at least one of the teeth of the ratchet in accordance with the denomination of the coin, means provided in the pawl means to move the pawl means beyond the previously engaged tooth upon movement of the pawl means away from the tooth to provide successive resetting of the indicator upon successive insertion of multiple coins of different denominations.

5. In an automatic parking meter adapted to receive multiple coins of different denominations for indicating selective amounts of time and comprising a movable indicator, a clock works for driving the indicator in one direction relative to a time scale, a ratchet movable with the indicator and provided with separate sets of teeth complementary to the different denominations of coins, pawl means cooperating with the ratchet in a released position of the pawl means to limit movement of the indicator in a direction opposite the first mentioned direction, means urging the indicator and ratchet in said last mentioned direction, means adapted to rotate a coin upon insertion thereof into the meter, means normally retaining the pawl means out of engagement with the ratchet and cooperating with the coin rotating means through the medium of the coin for releasing the pawl means into selective engagement with the teeth of the ratchet in accordance with the denomination of the coin, means provided in the pawl means to move the pawl means beyond the previously engaged tooth upon movement of the pawl means away from the tooth to prevent jamming of the pawl upon successive insertions of multiple coins.

6. In an automatic parking meter adapted to receive multiple coins of different denominations for indicating selective amounts of time and comprising a movable indicator, a clock works for driving the indicator in one direction relative to a time scale, a ratchet movable with the indicator and provided with separate sets of teeth complementary to the different denominations of coins, pawl means cooperating with the ratchet in a released position of the pawl means to limit movement of the indicator in a direction opposite the first mentioned direction, means urging the indicator and ratchet in said last mentioned di-

12

rection, means adapted to rotate a coin upon insertion thereof into the meter, means normally retaining the pawl means out of engagement with the ratchet and cooperating with the coin rotating means through the medium of the coin for releasing the pawl means into selective engagement with the teeth of the ratchet in accordance with the denomination of the coin, said pawl means having an elongated aperture to provide a backlash action to allow movement of the pawl beyond the engaged tooth upon movement of the pawl away from the tooth.

7. In an automatic parking meter adapted to receive multiple coins of different denominations for indicating selective amounts of time and comprising a movable indicator, a clock works for driving the indicator in one direction relative to a time scale, a ratchet movable with the indicator and provided with separate sets of various sized teeth complementary to the different denominations of coins, pawl means cooperating with the ratchet in a released position of the pawl means to limit movement of the indicator in a direction opposite the first mentioned direction, means re-setting the indicator and ratchet in said last mentioned direction, means adapted to rotate a coin upon insertion thereof into the meter, means normally retaining the pawl means out of engagement with the ratchet and cooperating with the coin rotating means through the medium of the coin for releasing the pawl means into selective engagement with the teeth of the ratchet in accordance with the denomination of the coin, said pawl means having an elongated aperture to provide a backlash action to allow movement of the pawl ahead of the engaged tooth upon movement of the pawl away from the tooth to prevent jamming of the pawl and to provide successive resetting of the indicator upon successive insertions of multiple coins.

8. In an automatic parking meter adapted to receive multiple coins of different denominations for indicating selective amounts of time and comprising a movable indicator, power driven clock works for driving the indicator in one direction relative to a time scale, a torsion spring for resetting the indicator in an opposite direction thereto, a ratchet movable with the indicator and provided with separate sets of teeth complementary to the different denominations of coins, a power driven plate, a trip lever adapted to release the plate through force applied to a coin inserted in the meter, lugs on the plate for rotating the inserted coin into engagement with a coin actuated lever, stop pawl means, means cooperating with the lever and the pawl means to provide movement of the pawl means for selective engagement with a set of teeth on the ratchet to provide for re-setting of the indicator in accordance with the denomination of the coin, and means cooperating with the coin lever to provide disengagement of the indicator from the clock works during actuation of the lever, means provided in the stop pawl means to move the pawl means ahead of the engaged tooth upon disengagement of the pawl means from the tooth to provide resetting of the indicator upon successive insertion of multiple coins of different denominations.

9. In an automatic parking meter adapted to receive multiple coins of different denominations for indicating selective amounts of time and comprising a movable indicator, a clock works for driving the indicator in one direction relative to a time scale, a ratchet movable with the in-

icator and provided with a plurality of sets of various sized teeth complementary to the different denominations of coins, means for resetting the indicator and ratchet in a direction opposite the first mentioned direction, indicator stop means cooperating with the ratchet in a released position of the indicator stop means to limit the movement of the indicator in said last mentioned direction, means normally retaining the indicator stop means out of engagement with the ratchet and responsive to a coin inserted in the meter for releasing the indicator stop means to allow engagement thereof with a selected ratchet tooth according to the denomination of the coin inserted, means provided in the indicator stop means to provide resetting of the indicator upon successive insertion of multiple coins of different denominations, and means for masking a part of one set of the ratchet teeth for one denomination of coin.

10. In an automatic parking meter adapted to receive multiple coins of different denominations for indicating selective amounts of time and comprising a movable indicator, a clock works for driving said indicator in one direction relative to a time scale, a ratchet movable with the indicator and provided with a plurality of various sized teeth complementary to the different denominations of coins, means for urging the indicator and ratchet in a direction opposite the first mentioned direction, indicator stop means cooperating with the ratchet in one position of the indicator stop means to limit the movement of the indicator in said last mentioned direction, and means responsive to a coin inserted in the meter for providing movement of the indicator stop means to provide for selective engagement thereof with at least one of the various sized ratchet teeth dependent upon the denomination of the coin, and means responsive to an expired time position of the indicator to be moved adjacent the time scale for denoting the expiration of the parking time.

11. In an automatic parking meter for receiving multiple coins of different denominations to indicate selective periods of time, and comprising an indicator movable relative to a time scale, a clock works for driving the indicator in one direction relative to the scale, a plurality of sets of various sized teeth providing selective positioning of the indicator in a direction opposite the first mentioned direction, resilient means for urging the indicator and said teeth in said last mentioned direction, a stop pawl means cooperating with at least one of the teeth of one of the sets in a released position of the stop pawl means to limit the movement of the indicator in the said

last mentioned direction, and means normally retaining the stop pawl means out of engagement with the teeth and responsive to the insertion of a coin for releasing the stop pawl limiting means in accordance with the denomination of the coin to provide for selective positioning of the indicator dependent upon the denomination of the coin with respect to the various sized teeth.

12. In an automatic parking meter for receiving multiple coins of different denominations to indicate selective periods of time, and comprising an indicator movable relative to a time scale, a clock works for driving the indicator in one direction relative to the scale, a ratchet carried by the indicator, a series of small teeth on the ratchet having a defined path of movement, a large tooth on the ratchet in aligned relationship with the small teeth and extending beyond the small teeth, a spring urging the indicator and ratchet in a direction opposite to the first mentioned direction to reset the indicator, a stop pawl, and means responsive to one denomination of coin inserted in the meter to provide movement of the stop pawl into the path of movement of the small teeth, and responsive to a second denomination of coin inserted in the meter to provide movement of the stop pawl into the path of movement of the large tooth to reset the indicator in accordance with the denomination of the coin inserted in the meter.

13. In an automatic parking meter for receiving multiple coins of different denominations to indicate a selective period of time, and comprising an indicator movable relative to a time scale, a clock works for driving the indicator in one direction relative to the scale, a ratchet carried by the indicator, a series of aligned teeth on the ratchet, the central tooth and the last tooth in said series being extended, a stop pawl, a spring urging the indicator and ratchet in a direction opposite to said first mentioned direction to reset the indicator, and means responsive to a coin inserted in the meter to provide movement of the pawl into engagement with one of the teeth of said series in accordance with the denomination of the coin.

GERALD A. HALE.
